US00D826257S

(12) **United States Design Patent** (10) Patent No.: **US D826,257 S**
 Thiel et al. (45) Date of Patent: **** Aug. 21, 2018**

(54) **DISPLAY SCREEN OR PORTION
THEREFOR WITH GRAPHICAL USER
INTERFACE**

(71) Applicant: **Altisource S.à r.l.**, Luxembourg (LU)

(72) Inventors: **Will Thiel**, Boston, MA (US); **Francois Silvain**, Boston, MA (US); **Tatiana Thomas**, Boston, MA (US)

(73) Assignee: **Altisource S.à r.l.**, Luxembourg (LU)

(**) Term: **15 Years**

(21) Appl. No.: **29/586,196**

(22) Filed: **Dec. 1, 2016**

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The broken lines showing the display screen or portion thereof with graphical user interface is provided for the purpose of illustrating environmental structure and forms no part of the claimed design.

1 Claim, 1 Drawing Sheet
